TRUCK CAB

Luther W. Stier, Rochester, and Charles M. Jordan, Birmingham, Mich., assignors to General Motors Corporation, Detroit, Mich., a corporation of Delaware

Application May 26, 1955, Serial No. 36,235

Term of patent 7 years

(Cl. D14—3)

Fig. 1 is a side elevation of a truck cab embodying our new design; and

Fig. 2 is a front view thereof.

The opposite side is similar to the side shown and the back constitutes a continuation of the wraparound window and the portions above and below the same.

The truck disclosed by means of broken lines is shown only for purposes of illustration.

We claim.

The ornamental design for a truck cab, substantially as shown and described.
